UNITED STATES PATENT OFFICE.

FRANCIS A. BARTHOLOMEW, OF BLOOMFIELD, NEW JERSEY.

SWITCH FOR CENTER-RAIL ELEVATED RAILROADS.

SPECIFICATION forming part of Letters Patent No. 400,164, dated March 26, 1889.

Application filed August 6, 1886. Serial No. 210,167. (No model.)

To all whom it may concern:

Be it known that I, FRANCIS A. BARTHOLOMEW, a citizen of the United States, and a resident of Bloomfield, in the county of Essex and State of New Jersey, have invented new and useful Improvements in Switches for Center-Rail Elevated Railroads, of which the following is a specification.

My invention relates to improvements in switches for elevated railways in general, but specially for that class thereof known as a "single-rail elevated road," in which the main weight of the load and rolling-stock is supported upon a single central rail elevated above two side rails.

The invention will be hereinafter fully described, and specifically pointed out in the claims, reference being had to the accompanying two sheets of drawings, in which—

Figure 1 represents a plan view of my improved switch placed in line with a main track, and showing also in dotted center lines its position when thrown to switch off a train from the main to a side track or branch line.

Fig. 2 is a plan view of the same in horizontal section on the line Z Z of Fig. 3 and looking downward. Fig. 3 is a vertical section on the line X X of Fig. 1. Fig. 4 is a detail cross-section of one of the transoms or cross-beams of the truss or the sub-structure of the swing-track or movable swinging portion of the switch, or as taken on the line y y of Fig. 1. Fig. 5 is an end view of the transversely-sliding portion or switch-carriage seen in the direction of arrow 1 of Fig. 6, the frame thereof being partly broken out on the line W W, and the rails on which the carriage slides being left out, so as not to crowd other details.

Fig. 6 is a side elevation of the same seen from the lines v v of Figs. 5, 7, and 8 in direction of arrows 2. Fig. 7 is a plan view of the same placed to correspond to Fig. 5 when looked down upon. Fig. 8 is a plan view of the movable parts underlying the switch-car-

riage and by which the latter receives its transverse movement automatically from the lateral throw of the swing-track.

A is the main track with center rail, a, and side rails, a'.

B is a side track with its center rail, b, and side rails, b'.

C is the swing-track or the swinging portion of the switch, the center rail and side rails of which are designated like those on the main track by letters a and a', respectively.

D is the switch-carriage arranged to move transversely to the switch-track, as will hereinafter appear, regulated automatically by the movement of the latter, so as to connect the rails a and a' of the main track and the swing-track with the corresponding rails, b and b', of the branch track. The switch-carriage has on its surface rail-pieces a and a' for connection with the rails of the main track and the swing-track when the latter switches onto the main track, and at the side of the said rail-pieces another set of rail-pieces, b' and b'', which, when the switch-carriage and the swing-track are moved to connect with the branch line, form a continuous rail of the side rails, a', of the main track and swing-track with the side rails, b', of the branch track, the center rail, b, on the switch-carriage at the same time simultaneously connecting in one line the center rail of the main track with the center rail of the swing-track and the center rail of the branch track. The position of the swing-track when moved in the direction of arrow 3 to connect with the branch track, (see Fig. 1,) is indicated by the dotted lines representing the center lines of the rail.

E represents one or more of the posts of the structure upon which the track is supported, the switch-carriage being arranged directly upon and above one of the said posts, and at the other end of the swing-track a plate, e', is secured upon the post for the end of the swing-track to rest upon and to move on, to facilitate which movement the swing-track is provided with the friction rollers or wheels c'. (See Fig. 1.)

The throwing of the switch—that is, the swinging aside of the swing-track—may be accomplished by suitable hand-operated mechanism; but I prefer to use for the purpose a hydraulic motor.

In Fig. 1 J is intended to represent such a motor, being in this case, for the sake of simplicity, shown as an oscillating cylinder whose piston, by its connecting-rod j, is pivoted or movably connected to the center

beam of the swing-track, so as to pull the latter when switching off to the branch track and push it when again switching onto the main track, in a manner easily understood by reference to Fig. 1.

The switch-carriage D is preferably arranged to slide or move upon rails e, secured upon the posts E, and to reduce friction it may be provided with friction rollers or wheels in like manner as the switch-track, as before described, and the transverse movement of the switch-carriage is effected automatically by the movement of the swing-track, the construction of which I will now proceed to describe.

The swing-track is built up of a center beam or compound girder, F, of iron, and iron side beams, G, parallel with the said center beam, F, the side beams being interconnected and firmly united by transoms f and diagonal braces g.

At the end of the swing-track, above the post E directly underneath the switch-carriage, the center beam, F, is provided with a strong bracket, having a perforated lug which, by a bolt, is pivoted at c upon the post E, said point c being the center for the motion of the swing-track.

To the end of the transoms f, and at intervals to the center beam, F, are secured upwardly-projecting inclined braces f' g', to which is secured the elevated center rail, a, the side rails, a', being secured upon wooden beams placed longitudinally above the supporting iron beams G upon wooden sleepers or cross-bars laid upon the flanges of the said iron beams G, the swing-track thus constructed being a strong self-supporting section, like a bridge-truss, spanning the distance between two end supports.

The side beams, G, are provided at the pivoted end of the swing-track with links c', connecting two bell-crank levers, H, which latter are pivoted at h, and are interconnected by a bar, I, which, by a bolt, i, is connected to a lug, d, of the switch-carriage D. (See Figs. 2, 5, 6, and 8.)

The operation is easily understood by reference to Figs. 1, 2, 7, and 8. When the engine J is started to move the swing-track in the direction of arrow 3, one of the side beams G pushes and moves the nearest lever H in the direction of arrow 4 and the other beam G pulls its nearest elbow-lever in the direction of arrow 5, thus moving the rod I, and also the switch-carriage D, attached to said rod, in the direction of arrow 6, until, when the side rails, a', and center rail, a, of the swing-track are exactly in line with the corresponding rails, b' and b, of the branch track B, the side-rail pieces, b', and center-rail piece, b, of the switch-carriage have got into position exactly in line with the corresponding rails, a' and a, of the swing-track C and the nearest portion of the main track A. It is evident that by moving the swing-track back again to the main track—that is, in a

direction opposite to arrow 3—the switch-carriage D will also be moved in a direction opposite to that indicated by arrow 6, and resume its position shown in Figs. 1 and 7. The rod I, which connects the elbow-levers H, is preferably made in sections, the portion thereof connected directly to the elbow-levers having sockets threaded inside, and the center portion, in which the bolt i enters, is provided on its ends with right and left threads, so that by turning the center portion in the said socket the length of the rod, and consequently the distance between its pivotal points of the elbow-levers H, may be adjusted to a nicety.

The construction of the sliding section or switch-carriage above described obviates pointed switch-rails and the open space otherwise needed between the switch-rail and stationary rail, as well as in the latter itself, to allow the flanges of car-wheels and locomotive-wheels to pass from the main track to a side track, or vice versa, and which is a source of the danger of derailment.

The sliding section or switch-carriage herein described and shown should not be confounded with a switch-rail oscillable upon a stationary pivot at one end or in the center of the said switch-rail—for instance, such as shown in Patents Nos. 278,819 and 326,406, to which I lay no claim.

Having thus described my invention, I claim as new and desire to secure by Letters Patent—

1. The combination, with a main track and a branch track, of a swing-track or swinging section and a sliding section or switch-carriage, both moving simultaneously, the latter transversely to the former, substantially as and for the purpose set forth.

2. The combination, with a main track and a branch track, of a swing-track or swinging section and a sliding section or switch-carriage, both moving simultaneously, the latter operated automatically by the movement of the former.

3. The combination, with a main track and a branch track and with a swing-track or swinging section, and a sliding section or switch-carriage moving transversely to the track, of a hydraulic motor, J, having piston-rod connected to the said switch-track, substantially as and for the purpose set forth.

4. In combination with a main track and a branch track, a rigid swing-track pivoted at one end in its longitudinal center line to a stationary part of the structure and supported at its other end to admit of a circular movement horizontally on the said pivot, a sliding section or switch-carriage movable transversely to the track at the pivoted end of the said swing-track, and movable connections, substantially as described, transmitting motion from the said swing-track to the said switch-carriage, as hereinbefore set forth.

5. In combination with a main track and a branch track and with a switch-carriage, D,

provided with switch-rails *a a'* and *b b'* and arranged to move transversely to the track, the swing-track *C*, pivoted at one end in its longitudinal center line to a stationary part 5 of the structure and having at opposite sides of its pivot-point pivotal links *c'*, the elbow-levers *H*, pivoted to the said structure, and the rod *I*, pivoted to the said switch-carriage for operating the latter automatically by the

10 movement of the said switch-track.

6. In combination with a main track and a branch track and with a switch-carriage, *D*, provided with switch-rails *a a'* and *b b'* and arranged to move transversely to the track, 15 the swing-track *C*, composed of the center beam or girder, *F*, and side beams, *G*, connected by suitable transoms and braces, *f* and *g*, supporting a center rail, *a*, and side

rails, *a'*, and pivoted with one end of the said central beam to a stationary part of the 20 structure, the links *c'*, pivoted to the ends of the said side beams, *G*, the elbow-levers *H*, connected to the said links and pivoted upon the structure, and the bar *I*, movably connected to the said elbow-levers and also to the said 25 switch-carriage, substantially as and for the purpose herein set forth.

In testimony that I claim the foregoing as my invention I have signed my name, in presence of two witnesses, this 5th day of Au- 30 gust, 1886.

FRANCIS A. BARTHOLOMEW.
